UNITED STATES PATENT OFFICE.

WILLIAM F. OEFTER, OF DETROIT, MICHIGAN.

GAS-LAMP CONTROL AND IGNITER.

1,132,485.

Specification of Letters Patent. Patented Mar. 16, 1915.

Application filed March 9, 1914. Serial No. 823,518.

To all whom it may concern:

Be it known that I, WILLIAM F. OEFTER, a citizen of the United States of America, residing at Detroit, in the county of Wayne 5 and State of Michigan, have invented certain new and useful Improvements in Gas-Lamp Controls and Igniters, of which the following is a specification, reference being had therein to the accompanying drawings.

10 This invention relates to gas-lamp controllers and igniters and more particularly to a combined gas control and igniter adapted for both regulating the flow of gas to a burner, such as that of an automobile lamp, 15 and electrically igniting the gas thus supplied to the burner.

It is among the objects of the invention to provide an improved combined gas control and igniter of the type mentioned, 20 which may be conveniently and economically connected into a circuit, such as that leading to one of the spark plugs, employed in the normal functions to the engine.

The invention further resides in the novel 25 arrangement and combination of parts, and various features of construction hereinafter set forth.

In the drawings,—Figure 1 is a side elevation of the combined controller and igniter; Fig. 2 is a longitudinal section there- 30 through; and Fig. 3 is a diagrammatic view showing the controller and igniter applied to a multi-cylinder engine and a plurality of burners.

35 In the diagrammatic view, A represents the multi-cylinder engine of an automobile, B the dash and C C' the gas burners for the headlights. Acetylene or other suitable gas is supplied to the burners C and C' from the 40 storage tank C² through conduits C³, C⁴ respectively which communicate with the main inlet conduit C⁵ through a valve-controlled chamber D. This chamber D is prefer- 45 ably formed as a part of the combined controller and igniter E, one end of said valve chamber being provided with integral lugs D' D² which are secured to the insulating body E' of the controller E by screws E¹, E². The outer end of the chamber D is provided 50 exteriorly with threads D³ adapted to receive a coupling member for securing the main inlet conduit C⁵. Connection between the interior of the chamber D and the conduits leading to the lamps is made through 55 a nipple D⁴ leading from one side of the valve chamber at a point above the valve seat

F. As far as the action of the controller is concerned, the chamber D is always in open communication with the conduits C³ and C⁴ but the flow of gas through the opening F' which connects the valve chamber with the inlet conduit C⁵ is adjustably controlled by a valve G. As shown in Fig. 2 this valve is of the needle type and is moved toward or from the seat F when the valve 60 stem G' is rotated, there being the usual threaded engagement between the valve stem and the inner wall D⁵ of the chamber D. The valve stem extends through a bearing G² carried by the insulating body E of 65 the controller and is turned by means of the operating knob or button H.

The connection between the valve stem and the operating button is arranged to cause the stem to rotate with the operating 70 button but permitting the free relative, longitudinal movement of said parts. Thus, the operating button H is provided with a cylindrical housing H' fixedly secured within the button, said housing having its open 75 end partially closed by a bar H². This bar is carried by the housing H' and engages a flat bearing face I formed by recessing a portion of the stem G'. Beyond the plane of the bar H² the remaining portion 80 of the stem G' which extends within the housing H' is of reduced cross-section and is surrounded by a coil spring J. One end of this spring abuts against the end wall 85 of the operating button H, and the other end abuts against a bearing washer J' loosely sleeved upon the reduced portion of the stem G' and having its movement toward the open end of the recess limited by a shoulder J² on the stem G'. Upon rotating 90 the button H to either the right or left, the valve G will be opened or closed accord- 95 ingly, the amount of opening of the valve being regulated by the degree of rotation of the button, since the engagement of the bar H² with the bearing face I of the valve stem will cause the stem and button to rotate together. The button, however, is free 100 to move inward, without effecting any ad- justment of the valve stem, and can be moved inward irrespective of what posi- 105 tion of rotation the parts may be in. The independent longitudinal movement of the button is employed for ignition control in the following manner: An annular contact 110 maker K is carried by the operating button, being secured thereto by suitable means such

as the screws K' K². Inasmuch as the operating button H is made of insulating material and is provided with an integral flange H³ which extends between the casing H' and the contact maker K, the latter is completely insulated from the valve-operating mechanism. A plurality of contact members L L' L² and L³ are carried by the insulating body E and are positioned in operative relation to the contact member K. These members L L' L² and L³ extend through the insulating body E and on the opposite side thereof terminate in binding posts M M' M² and M³ respectively. The lead from the binding post M runs to the lamp C and that from the binding post M' to the lamp C', while the binding post M² is connected to a suitable source of current. In order to reduce the number of parts necessary I preferably utilize the magneto circuit and avoid the use of additional coils by connecting the contact maker K in the leads to one of the spark plugs N. Thus as shown in the diagram, the binding post M² is connected to the lead from the magneto, and the binding post M³ to the spark plug. As it is desired to use the same contact member for connecting the contact maker to the magneto lead in all positions of adjustment of the operating button, the binding post M² is made hollow and has sleeved therein a metallic member O normally pressed outward against the contact maker K through the medium of a spring O' housed within the hollow post. Since the contact maker K is of annular form and extends outward over the metallic member O, it is obvious that the contact maker and the metallic member O will be in electrical contact in all positions of rotative and longitudinal adjustment of the operating member H and will in no way interfere with either adjustment. The contact L³ has a portion extending upon the opposite side of the contact maker from that of the metallic member O. As the operating button H is normally pressed outward by means of the spring J, the circuit from the magneto to the spark plug N would be normally closed. However, the inward movement of the operating button will compress the spring O' and while maintaining contact with the member O, the contact maker will be moved out of contact with the member L³ and thus break the circuit to the spark plug.

It is desirable that the circuit to the spark plug N be broken upon the inward movement of the operating button H since such movement is utilized for the purpose of igniting the burners C and C'. The contact member L is provided with a ball-contact T resiliently pressed outward beyond the face of the contact into the path of one edge of the contact member K, while the contact L' is sufficiently shorter than the contact L

so that the circuit from the magneto to the lamp C will be broken prior to the closing of the circuit between the magneto and the lamp C'. In the arrangement of parts as above described it will be seen that a single pressing in of the operating button H will successively break the circuit to the spark plug N, close the circuit to the lamp C and then reopen the same and finally close the circuit to the lamp C'. This operation is moreover accomplished irrespective of the position of rotative adjustment of the operating button H. While I have shown circuits leading to two lamps only, it is obvious that a greater number of lamps could be successively lighted in a similar manner.

The contact maker and contact members are inclosed within a suitable housing R, the operating member H extending outward through an aperture R' in the casing. In attaching the device to an automobile the insulating body E which carries the entire structure, is secured to the dash or other desired part by means of bolts S, the acetylene tank or other source of gas supply connected to the outlet D³ and the conduits running to the burners connected to the nipple D⁴, the lead from the magneto to one of the spark plugs connected to the binding post M² and the binding post M³ connected to said spark plug. The lead wires are run to the binding posts T and T' on the burners C and C' respectively, these burners being provided with a sparking device and properly grounded on any convenient part, such as the crank case A'. When the driver desires to light the lamps the operating button H is rotated to open the valve G to permit of the desired flow of gas to the lamp burners. The button is then pushed inward, which will result in breaking the circuit to one of the spark plugs and successively igniting the gas in each of the lamps. Upon releasing the pressure upon the operating button H it will automatically return to its normal position through the action of the spring J and will carry with it the contact maker K, immediately closing the circuit to the spark plug, thus permitting the engine to operate in its normal manner. After lighting the lamps the flow of gas to the burners can be regulated entirely independent of any change in the ignition.

While I have shown my controller connected into the leads of one of the spark plugs of an engine, I do not desire to limit my protection to that particular element, and it is also obvious that other sources of current than the magneto may be employed within the scope of my invention.

What I claim as my invention is—

1. A combined gas and ignition controller, comprising a gas-control valve, an operating member adapted on rotative adjustment to operate said gas-control valve, a contact

maker carried by said operating member, a depressible contact member having a lead from a source of current and being in contact with said contact maker in all positions of adjustment of the latter, means for resiliently pressing said contact maker outward, a second contact member having a lead to a main ignition device and engaging said contact maker in the outward position of the latter, and a plurality of other contact members having leads to auxiliary ignition devices and positioned in the path of the contact maker so as to be successively engaged by said contact maker upon the longitudinal adjustment of the latter.

2. A combined gas and ignition controller, comprising a gas-control valve, a longitudinally and rotatively adjustable operating member adapted on rotative adjustment to operate said gas-control valve, a contact maker carried by said operating member and normally spring-pressed outward, a depressible contact member having a lead from

a source of current and engaging said contact maker in all positions of rotative and longitudinal adjustment of said contact maker, a second contact member having a lead to a main ignition device and being positioned to engage said contact maker only in the outward position of the latter, a third contact member having a lead to an auxiliary ignition device and being engaged by said contact maker only on the inward position of the latter, and a fourth contact member having a lead to an auxiliary ignition device, said fourth contact member having a depressible ball-contact engaged by said contact maker when the latter is out of contact with the second and third contact members.

In testimony whereof I affix my signature in presence of two witnesses.

WILLIAM F. OEFTGER.
